CLAIM

The ornamental design for a campaign button, as shown and described.

DESCRIPTION

FIG. 1 is a front elevational view of a campaign button showing my new design.

FIG. 2 is a side elevational view thereof.

FIG. 3 is a rear elevational view thereof.

FIG. 4 is a bottom plan view thereof.

FIG. 5 is a cross sectional view taken along lines 5—5 on FIG. 1.

The broken line showing of indicia is for illustrative purposes only and forms no part of the claimed design.

FIG. 1.

FIG. 2.

FIG. 3.

FIG. 5.

FIG. 4.
